Fig. 6

Fig. 7

FIG. 1 is a front plan view of a combined envelope and sheet for advertising showing my new design in folded position, the back being plain;

FIG. 2 is a plan view thereof in an unfolded position;

FIG. 3 is a plan view with the panel at the right thereof folded inward;

FIG. 4 is a plan view with the panel at the left of FIG. 2 folded inward;

FIG. 5 is a plan view of a second embodiment of the design of FIG. 1 in a position as described for FIG. 4;

FIG. 6 is a plan view of a third embodiment of the design of FIG. 1 in a position as described for FIG. 4;

FIG. 7 is a plan view of a fourth embodiment of the design of FIG. 1 in a position as described for FIG. 4.

The dash lines on the drawing represent perforations.
I claim:

The ornamental design for a combined envelope and sheet for advertisement, as shown and described.
